MICROPHONE

Robert Louis Deschamps, West Chicago, Ill., assignor to
Shure Brothers, Incorporated, a corporation of Illinois

Filed Nov. 8, 1961, Ser. No. 67,420

Term of patent 14 years

(Cl. D26—14)

FIGURE 1 is a top plan view of a microphone embodying my new design;

FIGURE 2 is a side elevational view;

FIGURE 3 is a bottom plan view;

FIGURE 4 is a rear elevational view; and

FIGURE 5 is a front elevational view.

The opposite side from that shown in FIGURE 2 is substantially identical in design and appearance to that shown in FIGURE 2.

The essential features of my design reside in the portions shown in solid lines.

A further feature of my design resides in the recessed groove on the body of the microphone outlined by a raised square beading which extends from the groove in the upper

portion of the microphone to the cord outlet. This feature is clearly shown in FIGS. 1, 2, 4 and 5.

I claim:

The ornamental design for a microphone, substantially as shown and described.
